Atty.

UNITED STATES PATENT OFFICE.

ALBERT D. SMITH, OF DETROIT, MICHIGAN.

ELEVATION ADJUSTMENT FOR SEWING-MACHINE FEED.

1,417,865.

Specification of Letters Patent. Patented May 30, 1922.

Application filed July 30, 1918. Serial No. 247,426.

To all whom it may concern:

Be it known that I, ALBERT D. SMITH, a citizen of the United States, residing at Detroit, in the county of Wayne and State of Michigan, have invented certain new and useful Improvements in Elevation Adjustments for Sewing-Machine Feed, of which the following is a specification.

This invention pertains to feed mechanism for sewing machines, and has more particular reference to adjusting the elevation of the feed of a mechanism characterized by the inclusion of an oscillating rock shaft and a connection therefrom to the feed member for raising and lowering the latter, and a motion-train from the driving shaft for oscillating the rock shaft.

The primary object of the invention is to provide a simple and improved means for adjusting the degree of elevation of a feed member of the character described, whereby a defective feed movement caused by wear of the joints and parts may be quickly and easily remedied by a simple adjustment, and also whereby the feed may be quickly adjusted to the correct elevation for various distinct classes of sewing, such as for household and factory use and for fine and heavy materials.

30 Referring to the drawing,—

Figure 1 is an end elevation of a sewing machine equipped with the preferred embodiment of my improvement;

Fig. 2 is a full size plan sectional view taken on the line 2—2 of Fig. 1; and

Fig. 3 is a vertical sectional view on the line 3—3 of Fig. 2.

My present improvement relates particularly to means for varying the elevation of the feed member in a simple and effective manner. In the drawing, the feed member, indicated in general by reference character 5, is pivotally connected at its forward end to a crank arm 6, fixed to a feed-motion rock shaft 7 and is pivotally connected at its rear end through the agency of a translating link 8 and crank arm 9 to an elevation rock shaft 11. These rock shafts 7 and 11 are driven from the needle-bar driving shaft 50 through the agency of separate motion-trains, not shown in this case, which produce a four-motion feed movement. The means for operating the rock shaft may be of any suitable or preferred construction, 55 such for example as described in my co-pending application, Serial No. 247,427,

filed July 30, 1918. The mechanism shown in said application oscillates the crank arm 6 backwardly and forwardly to advance and retract the feed member and oscillates the 60 crank arm 9 upwardly and downwardly to raise and lower said member. In my co-pending application, means is provided for varying the length of the forward stroke and for reversing the direction of feed, these 65 variations being effected by changing the throw of the crank arm 6.

The crank arm 9, however, has a constant motion, and the purpose of the present invention is to provide a simple means, preferably arranged in the connection between this crank arm and the feed member, for relatively adjusting these parts to vary the elevation. It will be manifest that by varying the elevation of the feed member, the 70 toothed or roughened portion 12 thereof will be projected more or less above the throat plate 13 during the feed movement so as to engage the work with the proper pressure. This relative adjustment is obtained by shortening or lengthening the 75 distance between the pivots 14 and 15 at the upper and lower ends of the link 8. The pivotal relation between the feed member and the link 8 at the upper end 14 remains 80 constant. The pivot 15, however, is preferably in the form of a pivot bolt having a cylindrical shank 16 freely rotatable in the arm 9 and a reduced threaded end 17 passing through an elongated slot 18 in the link 80 8. A nut 19 on the threaded end 17 fixedly 85 clamps the link 8 against the shoulder 21 on the pivot bolt. Thus, while the link 8 is fixed to the pivot bolt 15, the latter is free to oscillate in its connection with the crank 90 arm 9.

It will be manifest that by loosening the nut 19 the link 8 may be vertically adjusted relatively to the crank arm 9 to vary the elevation of the feed member and that after 100 the nut 19 is tightened to secure the pivotal relation between the link 8 and the crank arm 9, these parts are still free to function in the usual way. While the construction thus provided is exceeding simple, nevertheless, it accomplishes a very desired object and is thoroughly practical for the purpose and is simple and easy to adjust.

I claim:

1. In a sewing machine feed mechanism, 110 the combination of a feed member, a rock-shaft having a crank arm, a pivot bolt in

the end of said crank arm, a link pivotally connected at one end with the feed member and having an elongated opening through which the threaded end of said bolt passes, and a nut on said threaded end for fixedly securing the link to the pivot bolt, which latter is freely pivotal on said crank arm.

2. In a sewing machine feed mechanism,
10 the combination of an elevation rock-shaft,
a feed-motion rock shaft, a feed member,
a crank arm fixed to the feed-motion rock-
shaft and pivotally connected directly to

the feed member, a crank arm fixed to the elevation rock-shaft, and a link pivotally connected at its ends directly to the elevation crank arm and to the feed member, the pivotal connection between the link and said crank arm comprising a pivot bolt adjustably secured in a slot in said member and pivoted in said crank arm, whereby the distance between the pivotal connections of said link may be varied for directly varying the elevation of the feed member.

ALBERT D. SMITH.
